UNITED STATES PATENT OFFICE.

JOSHUA MERRILL, OF BOSTON, MASSACHUSETTS.

IMPROVEMENT IN CASKS, BARRELS, &c.

Specification forming part of Letters Patent No. 58,450, dated October 2, 1866.

To all whom it may concern:

Be it known that I, JOSHUA MERRILL, of the city of Boston, in the county of Suffolk and State of Massachusetts, have invented certain Improvements in Casks, Barrels, and Kegs suitable for holding and transporting liquids; and I do hereby declare that the following is a full and correct description thereof, reference being had to the annexed drawings, making a part of this specification, and to the letters of reference thereon.

My invention consists of several improvements, whereby casks, barrels, and kegs used to hold and transport liquids are more effectually protected from leakage at the joints than casks, barrels, and kegs made with the well-known plain and flagged joints commonly used:

First, in a lapped-jointed cask, barrel, or keg, substantially as herein described, the lapped joints, consisting of a lip and rabbet formed upon the joints of the staves and head-pieces (if the heads be made of more than one piece) by rabbeting said staves and head-pieces, and in contradistinction from the tongued and grooved joint of the improved casks for which Letters Patent of the United States were granted to me, bearing date the 29th day of May A. D. 1866. Second, in combining, with the joints of a lap-jointed cask glue or other similar gelatinous cement, applied to said joints before the cask is put together, whereby the lapped joints when driven up are cemented firmly together and rendered more secure against the leakage of petroleum, alcohol, and other similar fluids, resisted by glue or gelatinous cements. Third, in combining with the joints of a lapped-jointed cask a cement of shellac, rosin, or other similar resinous cement, applied to the lapped joints before the cask is put together, whereby the lapped joints are rendered more secure against leakage of beer, molasses, or other watery fluids, which such resinous cements resist.

But more particularly to describe my invention, I will refer to the drawings, of which Figure 1 is a top view of the cask; Fig. 2, a cross-section; Fig. 3, a vertical section through the heads and staves, and Fig. 4 a section of a stave.

The staves *a* are each made with a lip, *b*, and rabbet *c* at each joint, as shown in the drawings, so that the lips and rabbets of the joints

of one stave make lapped joints with the lips and rabbets of the next staves.

The heads *d*, when made in pieces, are also jointed by a lip, *e*, and rabbet *f*. Dowel-pins *g* may also be used, as usual, in putting the head-pieces together.

The staves may be made in the ordinary way, and rabbed after they are plane-jointed, either by a rabbeting-plane or by machinery which I have devised, and which will form the subject-matter of another application for a patent. But the casks may be made sufficiently well by steaming the staves, bending them by rollers, and plane-jointing them by machinery, prior to rabbeting them, as practiced in large cooperages.

Although the staves so jointed make a tighter cask, barrel, or keg than plane-joints, I prefer to cement the lapped joints by cement applied to the joints before the cask is put together, so that the driving up of the hoops squeezes the cement into the pores of the joints which, while affording security from leakage, imparts great strength to the cask.

When the casks are to be used for holding and transporting petroleum, alcohol, and fluids that do not dissolve glue or other gelatinous cements, I apply a solution of hot glue to the joints, by dipping, or with a brush, just before setting up the casks. When the staves are properly made and jointed, there is very little difficulty in trussing the cask before the glue sets, especially when the staves have been bent by machinery.

When the casks, barrels, or kegs are to hold and transport beer, molasses, or other watery liquids, I cement the lapped joints together with shellac or rosin, or other suitable resinous substances.

In making the shellac solution, I prefer to mix together, in about equal proportions, alcohol ninety-five per cent. and coal-tar, benzole, or naphtha, of about 32° Baumé, and to one pint of this mixture I put in a pound to a pound and a half of common gum-shellac. This makes a good thick varnish, and does not dry so rapidly as shellac dissolved in alcohol alone, thus giving more time to set up the cask after the cement is applied to the joints. Shellac will, however, answer, if dissolved either in alcohol or caustic ammonia.

Rosin-cement may be made by dissolving,

in a pint of common naphtha, one and a-half pound of the rosin of commerce; or gum-dammar will answer as well.

The casks made as above described may be coated inside by a coating of glue or shellac, according to the liquid the cask is designed for. The coating of the inside is well known, and not necessary to be described, except to say that it may readily be done with glue, by pouring into the cask a few gallons of hot glue-solution, and then, by putting in the bung tight and rolling the cask about, the air within, being heated by the hot glue, forces it into the pores of the interior surface of the heads and staves.

I claim as of my invention and improvement—

1. In casks, barrels, and kegs used for holding and transporting fluids, the improved cask, substantially as described, having lapped

joints formed by a lip and rabbet, substantially in the way and for the purposes described.

2. In combination with the lapped joints of lapped-jointed casks, substantially as described, a coating or stuffing of glue, or similar gelatinous cement, applied to the lapped joints, substantially as described, whereby said joints are firmly glued or cemented together.

3. In combination with the lapped joints of lapped-jointed casks, substantially as described, a coating or stuffing of shellac, rosin, or other similar resinous cement, applied to the lapped joints, substantially as described, whereby the lapped joints are more securely protected against leakage.

JOSHUA MERRILL.
